(57) CLAIM

I claim the ornamental design for the holder for protective lid, as shown and described.

DESCRIPTION

FIG. 1 is a perspective view of a holder for protective lid showing my new design;

FIG. 2 is a front elevational view thereof;

FIG. 3 is a sectional view taken along line 3—3 in FIG. 2 thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
